CLAIM

I claim the ornamental design for a personal computer case, as shown and described.

DESCRIPTION

FIG. 1 is a perspective view of the personal computer case according to this invention.

FIG. 2 is a top view of the personal computer case.

FIG. 3 is a front view of the personal computer case.

FIG. 4 is a rear view of the personal computer case.

FIG. 5 is a left side elevation view of the personal computer case; and,

FIG. 6 is a right side elevation view of the personal computer case.

The broken line drawings of computer elements in FIGS. 2, 3, and 4 are for illustrative purposes only and form no part of the claimed design.
